UNITED STATES PATENT OFFICE.

CHARLES A. WRIGGITT, OF PHILADELPHIA, PENNSYLVANIA.

PUMP.

SPECIFICATION forming part of Letters Patent No. 617,212, dated January 3, 1899.

Application filed June 16, 1896. Serial No. 595,760. (No model.)

To all whom it may concern:

Be it known that I, CHARLES A. WRIGHT, of the city and county of Philadelphia and State of Pennsylvania, have invented an Improvement in Pumps, of which the following is a specification.

My invention has reference to pumps; and it consists of certain improvements, which are fully set forth in the following specification, and shown in the accompanying drawings, which form a part thereof.

The object of my invention is to provide a mechanical construction of pump especially adapted to pump volatile liquids under high pressure, such as is necessary in vapor-launches or machinery employing volatile vapor as the source of power.

Heretofore difficulty has been experienced from the fact that the stuffing-boxes of pumps employed for this purpose have been on the pressure side of the piston, and consequently it was difficult to secure the pump against leakage of the liquid. Where water is the fluid to be vaporized, this loss is of no moment; but when alcohol or highly-volatile spirits are employed it is a matter of the greatest importance, as the same fluid is continuously used over and over again, and none of it must be permitted to escape.

In carrying out my invention I provide a pump-chamber and pump-piston and necessary valves so as to be single-acting, and arrange the operating parts for the piston within the pump-chamber and upon the suction side, so that the rock-shaft thereof and its stuffing-box shall also open or extend into the suction-chamber of the pump.

My invention will be better understood by reference to the accompanying drawings, in which—

Figure 1 is a sectional elevation of my improved pump, taken on line xx of Fig. 3. Fig. 2 is a side elevation of my improved pump, and Fig. 3 is a plan view of same.

A is the cylinder of the pump, and opens at the bottom into the suction or inlet chamber B, into which the liquid is supplied by the suction-pipe O. The piston C moves in cylinder A and is connected to a rocking arm E by a link F. The rocking arm E is arranged within the inlet-chamber B and secured to the shaft D, journaled in the said inlet-

chamber, and one end of said shaft is extended to the outside of the chamber and packed by the stuffing-box P. This rock-shaft D has secured upon its outer end an arm or lever Q, which is pulled upward by the spring T and downward by an eccentric R and rod S. This latter action is secured by having the rod S fit loosely through a hole in the arm or lever Q and provided with a collar s at the top, which catches upon the lever to force it down. In the upstroke of the rod S the collar s may leave the lever O and the spring T be alone relied upon for pulling the said arm or lever O upward. In this manner the suction action of the piston is positively produced by the eccentric; but the forcing or pressure action of the piston is controlled by the spring T, and hence is always constant. This method of operating the rock-shaft is of course not essential, but is that which I commonly employ. It is of course evident that the piston-rod of the piston might pass directly through a stuffing-box, as usual, but I prefer to use the rock-shaft shown in this application, because the bearings are more durable and it is easier to make a tight joint at the stuffing-boxes than where the shaft reciprocates.

The cylinder of the pump also contains parallel to it a suction-port or passage-way G, opening at the bottom into the inlet-chamber B and provided at the top with a check-valve H. The upper end of the cylinder is covered with a cap I, which is recessed on the bottom to form a chamber J, which incloses the check-valve H and opens into the top of the cylinder A. The chamber J communicates through a port with the discharge-chamber K, arranged in the upper part of the cap I, and this port is provided with a check-valve L. A screw-plug M is fitted to the upper end of the cap, so as to tightly close the compartment K and yet permit at any time access to be had on the valve L. Opening from the chamber K on the side of the cap I is the discharge-pipe N.

It will now be observed that upon the descent of the piston C the liquid will be drawn through the pipe O into the chamber B and pass upward through port G and into the cylinder A by flowing under the valve H and through the chamber J. Upon the return stroke of the piston the liquid is forced up-

ward under the valve L into the discharge-chamber K and thence through the pipe N. In addition to this action the upward movement of the piston C creates a suction upon 5 the inlet-chamber B, and hence draws in from the suction-pipe O an additional supply of liquid. It will thus be seen that the descent of the piston C causes a flow of the liquid from the inlet-chamber into the upper part of the 10 cylinder and then in its upward stroke discharges the said liquid through the discharge-pipe N. In this latter action the additional liquid necessary to keep the pump filled is drawn in through the suction-pipe O. It is 15 quite evident that on starting the pump the suction created by the piston alone will cause the flow of the liquid through the supply-pipe O and put the pump into operative condition.

By my improved construction I secure 20 great simplicity, and at the same time the discharge side of the pump has no connection with the stuffing-box, and consequently there never is a great pressure acting to cause leakage of the liquid through said stuffing- 25 box.

I do not confine myself to the minor details of construction, as they may be modified without departing from the spirit of my invention.

What I claim as new, and desire to secure 30 by Letters Patent, is—

In a pump, the combination of the cylinder-body formed with the long cylinder A and long parallel tubular passage-way G and an inlet-chamber at the bottom into which said cylinder and passage-way open, a head detachably secured to the top of the cylinder-body and formed with a shallow clearance on its under side connecting with the cylinder unobstructedly and also with the tubular passage-way to form a suction-chamber and further having a discharge-chamber upon its upper part connected with the suction-chamber by a valved passage-way provided with a lateral discharge-port, a screw-plug M fitting into the 40 top of the discharge-chamber to seal it and hold the valve in place, a piston in the cylinder, a valve in the tubular passage-way held in working position by the upper wall of the suction-chamber, a rock-shaft extending into 45 the inlet-chamber, and connecting means between the rock-shaft and piston.

In testimony of which invention I hereunto set my hand.

CHARLES A. WRIGHT.
